UNITED STATES PATENT OFFICE.

CHARLES SISSON, OF PROVIDENCE, RHODE ISLAND, ASSIGNOR TO CHIPMAN,
CALLEY & CO., OF ROCKLAND, MASSACHUSETTS.

DESIGN FOR TAPE.

SPECIFICATION forming part of Design No. 22,027, dated November 29, 1892.

Application filed September 1, 1892. Serial No. 444,846. Term of patent 7 years.

To all whom it may concern:

Be it known that I, CHARLES SISSON, a citizen of the United States, residing at Providence, in the county of Providence and State 5 of Rhode Island, have invented and produced a new and original Design for Tapes or Similar Articles, of which the following is a specification, reference being had to the accompanying drawing, forming part thereof.

10 The drawing is a view of a piece of tape, showing my new design.

The nature of my design is fully represented in the accompanying drawing, to which reference is made; and it consists in groups of 15 shortlines arranged longitudinally of the tape or similar article, forming outline figures of

contrasting colors, indicating kangaroos seated on their haunches, extending through the central portion of the tape or similar article.

In the drawing, A represents the strip of 20 tape or similar article, and B B are outlines of different color to the body of the tape, representing kangaroos seated on their haunches.

What I claim is—

The design for tapes and similar articles, 25 as herein shown and described.

In witness whereof I have hereunto set my hand.

CHARLES SISSON.

Witnesses:

HENRY J. MILLER,
M. F. BLIGH.
